UNITED STATES PATENT OFFICE.

JOHN J. ALEXANDER, OF HOBOKEN, NEW JERSEY, ASSIGNOR TO ARCHIBALD MACINNES, OF NEW YORK, N. Y.

CLOSURE APPARATUS.

Application filed January 7, 1925. Serial No. 980.

This invention relates to apparatus for effecting closures and more particularly to apparatus designed for use in connection with receptacles and the like which are closed by means of a blank, the edges of which are crimped about an adjoining edge of the receptacle.

It is an object of the present invention to provide an apparatus which will effect such closures rapidly and effectively.

Other objects and advantages of the invention will appear hereinafter.

A preferred embodiment of the invention selected for purposes of illustration is shown in the accompanying drawings, in which,

Figure 1 is a plan view of the device,

Figure 2 is a side elevation,

Figure 3 is a section on the line 3—3 of Figure 1, and

Figure 4 is a detailed sectional view showing one of the arms in operation.

Referring to the drawings the closure apparatus comprises a base plate 1 provided around its outer periphery with a plurality of bosses 2 in each of which is pivoted an arm or lever 3. At one end the arm is provided with a head 4 which is grooved to provide a face 5 adapted to engage the edge 30 of the closure blank as hereinafter explained.

The plate 1 is also provided with a flange 6 which may be cylindrical in shape forming a cup 7 at the center thereof. The flange 6 is provided with a series of slots 8 through which the ends of the arms 3 project into the inside of the cup 7.

Mounted loosely within the cup is a cup-shaped member 9 having a rounded bottom 40 and provided with a cylindrical flange 11 extending upwardly into engagement with the under faces 12 of the ends of the arms 3. The cup-shaped member 9 forms a cam by which the arms 3 may be operated and is provided with a lever or handle 13 and is provided with a lever or handle 13 by means of which the device may be operated.

For purposes of the present description of the invention the apparatus described has been shown in connection with a metallic receptacle 14 which it is desired to close with the metallic blank 15. The blank 15 may be provided as illustrated with a U-shaped flange 16 adapted to fit over the beading 17 at the upper edge of the receptacle. The

U-shaped flange may terminate in a depending edge 18 which may extend completely around the blank or may be in the form of lugs or tabs formed in the blank. If desired, a gasket 19 of rubber or other suitable material may be laid in the flange 16 in order to more effectively seal the edge. It will be understood that the foregoing is illustrative merely of one form of receptacle and closure blank with which the apparatus described may be used and that, as will be apparent, the apparatus of the invention may be used effectively with other types of receptacles and closure blanks.

When in use the receptacle to be closed may be covered with a blank with which it is to be closed and the closure apparatus may then be lifted by means of the handles 20 and placed on top of the closure blank as illustrated in Figures 2 and 3. In this position it will be observed that the faces 5 are adjacent the depending edge 18 of the blank and that an inward motion of the heads 4 caused by lifting the inner end of the arms 3 will cause a bending and crimping of the edges of the blank. At the same time a compressive force will be exerted between the faces 5 and the faces 5' of the base plate tending to compress the gasket 19 to form an effective closure and seal as illustrated in Figure 4.

In order that the arms 3 may be rapidly and conveniently operated to perform the closure operation described, the cam member 9 and the lever 13 are provided. As will be observed, by swinging the lever 13 with a rotary movement, the arms 3 may be operated successively by a single complete rotation of the lever.

It is to be understood that the apparatus may be variously modified and embodied within the scope of the subjoined claims.

I claim as my invention.

1. Closure apparatus, comprising in combination, a base plate adapted to fit over a closure blank, a plurality of arms mounted thereon, said arms being provided with faces to engage the edges of said closure blank, and manually operable means including a cam and lever for operating said arms successively to crimp said edges to effect closure. 100

2. Closure apparatus, comprising in combination, a base plate adapted to fit over a closure blank, a plurality of arms mounted 105

thereon, said arms being provided with faces to engage the edges of said closure blank, and means including a cam and lever for operating said arms successively with a single rotary motion of said lever to crimp said edges to effect closure.

3. Closure apparatus, comprising in combination, a base plate adapted to fit over a closure blank, a plurality of levers pivoted thereon, said levers being provided with faces to engage the edges of said closure, and manually operable means including a cam and lever for operating said arms successively to crimp said edges to effect closure.

15 4. Closure apparatus, comprising in combination, a base plate adapted to fit over a closure blank, a plurality of levers pivoted thereon, one end of each of said levers being provided with a face adapted to engage the edge of said closure blank, and the other end of each of said levers being provided with a face to engage an actuating means, and cam means to engage said last named faces to actuate said levers successively to crimp the 25 edges of said blank to effect closure.

5. Closure apparatus, comprising in com-

bination, a base plate adapted to fit over a closure blank, said plate being provided with a projecting flange forming a cup at the center thereof, a plurality of levers pivoted 30 on said plate, said levers being provided at one end with faces to engage the edges of said closure blank and being provided at their other ends with actuating faces extending within said cup through slots in said 35 flange, and means to operate said levers including a cam mounted loosely within said cup and a lever fixed to said cam.

6. Closure apparatus, comprising, in combination, a base plate adapted to fit over a closure blank, an operating cam loosely mounted on said plate, a vertical operating lever secured thereto, a plurality of levers pivotally mounted on said plate, said levers being provided at one end with a face to 40 engage the edge of said closure blank and at the other end with a face to engage said cam.

In testimony whereof, I have signed my name to this specification this 5th day of 50 January 1925.

JOHN J. ALEXANDER.
